UNITED STATES PATENT OFFICE.

J. W. PRENTISS AND E. M. BIRDSALL, OF PENN YAN, NEW YORK.

IMPROVEMENT IN HARVESTERS.

Specification forming part of Letters Patent No. 43,225, dated June 21, 1864.

To all whom it may concern:

Be it known that we, J. W. PRENTISS and E. M. BIRDSALL, of Penn Yan, in the county of Yates and State of New York, have invented certain new and useful Improvements in Grain and Grass Harvesters; and we do hereby declare that the following is a full, clear, and exact description of the same, reference being had to the accompanying drawings, making a part of this specification, in which—

Figure 1 is a front view of a harvester, a portion of which is in section, as indicated by the line x x , Fig. 2; Fig. 2, a plan or top view of the same; Fig. 3, a vertical section of a portion of the same, taken in the line y y , Fig. 1; Fig. 4, a vertical section of a portion of the same, taken in the line z z , Fig. 1; Fig. 5, a vertical section of a portion of the same, taken in the line x' x' , Fig. 2.

Similar letters of reference indicate corresponding parts in the several figures.

This invention relates, first, to a novel and improved cutting device, the same consisting of two reciprocating cutters, placed one above the other and working in opposite directions and through slotted fingers provided each with a tongue, against which both the cutters act, the tongues being between the two cutters, and all arranged in such a manner as to admit of a short stroke and rapid movement of the cutters with a very moderate application or expenditure of power, thereby insuring the work being done in a perfect manner and without the liability of the cutting device becoming choked or clogged.

The invention relates, second, to an improved means employed for operating or driving the two cutters, which means consists of a rack at the inner end of each cutter and a vibrating toothed segment placed between the two racks of the cutters and gearing into the former, all being arranged in such a manner as to cause the necessary motion to be transmitted from the driving-shaft to the cutters in a very direct manner and with but little friction.

The invention relates, third, to a novel and improved means for connecting and disconnecting the traction-wheels of the machine with the sickle-driving mechanism, whereby the connection and disconnection above specified may be made with the greatest facility and without subjecting any of the gears and working

parts of the machine to the wear and tear hitherto consequent on such manipulation.

The invention consists, fourth, in an improved mode of hanging the axle of the traction-wheels of the machine, as well as the driving-shaft thereof, whereby all warping or springing of the frame of the machine is compensated for, and the working parts allowed to operate equally as well if the frame should warp or spring—a contingency of not infrequent occurrence—as if it retained its proper shape.

To enable those skilled in the art to fully understand and construct our invention, we will proceed to describe it.

A represents the frame of the machine, of rectangular form, and mounted on the two wheels B B', of equal diameter.

C represents the cutter-bar, the inner end of which is attached to a socket, D, composed of a horizontal bar, a, with an upright portion, b, at each end and a cap, c, secured to their upper ends. This socket D has an arm, E, projecting from its front side at right angles, said arm having a wheel, F, at its front end, which serves as a guide and a support for the cutter-bar, retaining the latter in a proper relative position with the earth and enabling the cutter-bar to rise and fall at its front edge to correspond to the inequalities of surface over which it may pass.

To the inner side of the socket D there is attached by a joint, d, one end of a rod, G, the opposite end of the latter being attached by a joint, e, to the left-hand side of the frame A at its back end, as shown clearly in Fig. 1. This arrangement admits of the cutter-bar rising and falling bodily, or at either end, to suit the surface of the ground over which it may pass. This feature, however, is equivalent to the double joint, as seen in the harvesting-machine generally known as the "Buckeye."

H represents fingers, which are attached to the cutter-bar C, and are each provided with two longitudinal slots, f f, so as to form a central tongue, g, as shown clearly in Fig. 5.

I I' are two cutters, which are constructed with the ordinary V-shaped teeth and work one above the other. The upper cutter, I, has its teeth h working in the upper slots f of the fingers H, and the teeth of the lower cutter work in the lower slots f of the fingers, the tongues g being between the teeth of the two

cutters. The teeth of the upper cutter, I, are beveled on their upper surfaces, while the teeth of the lower cutter are beveled on their lower surfaces, the cutting-edges of the teeth of both cutters working over the central tongues, *g*. These two cutters have a reciprocating motion and work simultaneously in opposite directions, the teeth of each cutter working from the center of one finger to the center of the one immediately adjoining. The cutters are operated by means of a vibrating double-gear segment, J, the shaft *i* of which is fitted vertically in the socket D. This segment J gears into racks *j j*, which are formed at the inner ends of the bars *k k*, to which the teeth of the cutters are attached, the segment J being provided at each end with a lip or flange, *l*, which retain or hold the bars *k* down upon the cutter-bar C. (See Fig. 4.)

The segment J is vibrated by having an arm, *m*, which is attached to the upper end of the shaft *i*, connected to a pitman, K, by means of a ball-and-socket joint, the ball *n* being at the end of the arm *m*, and the socket *o* being in the end of the pitman K. (See Fig. 4.) This pitman K is connected to a crank-pulley, L, on a shaft, M, the bearings N N of which are at the under side of the frame A, the shaft M having a pinion, O, at one end, which gears into a wheel, P, on the axle Q of the wheels B B'. By means of this arrangement of the two cutters I I' and the double-slotted fingers H, with a central tongue, *g*, between the teeth of the two cutters, we are enabled to get up a rapid motion of the cutters with a very moderate expenditure of power, and without the liability of having the cutters choked or clogged—a contingency of frequent occurrence with the ordinary single cutters. The central tongues, *g*, insure a clean, smooth cut, and in connection with the two cutters form, it is believed, a very simple and perfect cutting device for harvesters.

By operating the cutters I I' through the medium of the double vibrating geared segment J and racks *j j* very little friction is produced, and the parts are not liable to get out of repair or become deranged by use. By having the arm *m* of the shaft *i* of the vibrating segment J connected to the pitman K by a ball-and-socket joint, as shown, the segment J may be operated under the rising and falling of the cutter-bar with the least possible amount of friction, said joint compensating for the varying relative positions of the arm *m* and pitman K.

To the front end of the socket D there is secured by a joint, *p*, the back end of a rod, R, the front end of which is connected by a joint, *q*, to the left-hand side of the front part of the frame A. This rod R retains or holds the cutter-bar, preserving it from any strain under the draft movement of the machine, and at

the same time serving to greatly diminish side draft.

The wheels B B' are placed loosely on their axle Q, and the wheel P, into which the pinion O gears, is toothed at the inner side or edge of its periphery. This wheel P is not fitted directly on the axle Q, but is placed loosely on a clutch, S, on the axle, which clutch, when shoved outward or toward the wheel B, engages with the hub of the latter and connects it with the axle, the clutch S being allowed to slide through the wheel P, but the latter being connected with the former, so as to turn with it at all times. A similar clutch, T, also connects the other wheel, B', to the axle Q, and these clutches are operated simultaneously by means of rods *r r*, connected with a lever, U. By this arrangement the wheels B B' may be readily connected with and disconnected from the axle and the cutter-driving mechanism thrown in and out of gear with the greatest facility and without any injury to the working parts of the machine, as is frequently the case when a pinion—for instance, like O—is thrown in and out of gear with a wheel corresponding to P.

The axle Q of the wheels B B' is fitted in bearings V V, which are suspended between pivots *s s*, the latter passing horizontally through uprights *t*, attached to the frame A. (See more particularly Fig. 3.) This arrangement admits of the bearings adjusting themselves in line with the axle in case of the springing or winding of the frame A—a contingency of frequent occurrence. The shaft M is placed or hung in similar bearings, N.

Having thus described our invention, what we claim as new, and desire to secure by Letters Patent, is—

1. The combination of the two reciprocating cutters I I', both acting against central tongues, *g*, placed between them in the fingers H, as herein shown and described.

2. Operating the cutters I I' through the medium of the double-gear vibrating segment J and the racks *j j* on the bars *k k* of the cutters I I', substantially as described.

3. The wheel P, placed on the clutch S, which is fitted on the axle Q, and arranged, as shown, with or without clutch T, for throwing the cutter-driving mechanism in and out of gear with the wheel or wheels B B', without moving or adjusting the cutter-driving gearing, as set forth.

4. The adjustable bearings V V N N for the axle Q and shaft M, when constructed and applied to the frames of harvesters for the purpose specified.
